CLAIM

The ornamental design for a needle tip connector, as shown and described.

DESCRIPTION

This patent application is related to U.S. Design patent application Ser. No. 29/884,654, filed on Feb. 14, 2023, and titled “Micro-Needle Tip Assembly”; and U.S. Design patent application Ser. No. 29/884,655, filed on Feb. 14, 2023, and titled “Micro-Channeling Device”, both of which are incorporated herein by reference.

FIG. 1 is a perspective view of a needle tip connector shown in a position of use;

FIG. 2 is an enlarged view of the needle tip connector in FIG. 1;

FIG. 3 is an exploded view of the needle tip connector in FIG. 2 showing the ball and pushrod;

FIG. 4 is a sectional view of the needle tip connector in FIG. 2;

FIG. 5 is a perspective view of the pushrod of the needle tip connector in FIG. 1;

FIG. 6 is a front-side view of FIG. 5;

FIG. 7 is a back-side view of FIG. 5;

FIG. 8 is a right-side view of FIG. 5;

FIG. 9 is a left-side view of FIG. 5;

FIG. 10 is a top view of FIG. 5; and,

FIG. 11 is a bottom view of FIG. 5.

The broken lines in the drawings illustrate portions of the needle tip connector and its environment and form no part of the claimed design.

The thinner shading lines that appear on the ball head in FIG. 3 and the pushrod in FIGS. 5-11 illustrate 3-dimensional perspective and form no part of the claimed design.
